HOLD CARD HOLDER

Royce H. McBeath, Danville, Ky., assignor to F. D.
Kees Manufacturing Company, Beatrice, Nebr.,
a corporation of Nebraska

Application July 5, 1940, Serial No. 344,045

4 Claims. (Cl. 40—17)

My invention relates to hold card holders for the temporary storage of orders or other messages relating to the operation of electrical switches and circuits and particularly high voltage switches. Such orders and messages according to present practice are usually secured to any suitable support in proximity to the switch and the attachment of cards having thereon the orders or other messages is not only difficult but unsatisfactory. The operator usually wears rubber gloves while tying the card with a string or wire to the support. Inclement weather often makes the attachment very difficult, especially when the work must be done in the dark. The cards bearing thereon the orders are then exposed to wind and snow and rain with the result that the card is sometimes lost or that the order becomes obliterated so that it cannot be read.

In brief, it is my object to provide a container which may be easily attached to a support and which is adapted for the easy insertion and removal of the cards. It is also my object to make the container weatherproof to prevent the loss of the cards or the obliteration of the orders on the card. It is furthermore my object to provide the container with a transparent but weatherproof window through which the orders on the cards may be read without opening the container. It is also my object to provide a card holder which may be secured to boilers, stokers and any of many other operative devices for the mounting of instructions, either temporary or permanent.

Having in view these objects and others which will be pointed out in the following description, I will now refer to the drawing, in which

Figure 1 is a view in isometric projection showing the front portion of the hold card holder with a corner broken away to disclose the interior construction, the lid being in open position.

Figure 2 is a view in isometric projection showing the back of the hold card holder, the lid being shown in closing position.

Figure 3 is a transverse sectional view of the hold card holder, the view showing also the means for attaching the card holder to a support.

Figure 4 is a sectional view on the median vertical line through the upper portion of the card holder.

The device is formed of sheet metal of heavy gauge to withstand the rough usage to which it is subjected as well as to resist the action of the elements. The side edges 10 and the bottom 11 are integral in channelled construction and in U-form, constituting the frame of the device.

Inside this frame is a similar frame 12 which is L-shaped in cross section and which is secured to the side edges 10 and to the bottom wall 11 and spaced from the front flanges 13 of the bottom and sides to cooperate with the frame 12 to function as a window frame for the glass window 14. At the back of the card holder is a sheet metal back wall 15 which is welded as at 16 to the flanges 17 of the sides and bottom.

10 The back 15 is spaced from the window 14 to provide a receptacle for cards or the like which may be inserted or withdrawn from the holder through the open top.

15 The lid 18 is designed for closing the top opening of the holder but it is provided with wide depending flanges to prevent the entrance of rain and snow. It is secured to the holder to prevent its misplacement. As shown in Figure 1, the slotted link 19 is secured to both the holder and

20 the lid 18 by means of a pin 20 on the holder and a pin 21 on the lid. Each of the pins 20 and 21 has a sliding movement relative to the holder and the top but the combined length of the two slots is such that the flanges of the lid

25 cannot clear the upper edge of the holder until the lid is raised to the extreme height as permitted by the pins and slots. This prevents the accidental opening of the lid by gusts of wind or otherwise to expose the contents of the holder 30 to wind and snow and rain.

For conveniently securing the holder firmly in place, I provide a bolt 22 passing through the back wall 15 to cooperate with the nut 23. The head of the bolt 22 is countersunk in the back wall 15 so as to leave the inner surface of the back wall smooth and to provide no obstructions to the insertion or removal of cards.

Under present practice the operator of the switch attaches a card with instructions to whatever is convenient in location which is often the switch handle. The card is usually tied by a string or a wire to the support to warn a subsequent operator or workman, and since the operator must wear rubber gloves and often work in darkness, the attachment of the card to its support is not easy and none too secure. The card is exposed to all kinds of weather, often resulting in the loss of the card or the obliteration of the message on the card. With my 45 holder, the card is completely protected from weather at all times, and since the message can be read through the window, there is no need for its withdrawal with the wet or soiled hands of the operator. Cards with new instructions

50 55 may be readily inserted into the holder over the

previous card only by opening and closing the lid which requires several movements other than those of the elements.

High voltage switches are usually placed in elevated positions to be operated by means of a tubular stem such as a pipe which has a lever handle in its lower portion and which is within convenient reach of the operator. When such a tubular stem is employed, the attachment may be made as shown in Figure 3 to the tubular stem 24. For this purpose a metallic strap 25 is employed in the manner shown in Figure 3. This strap is apertured at its mid-point for the reception of the bolt 22, the strap being firmly secured by means of the nut 23. The strap, which possesses a certain resiliency, passes partly around the support 24 and its end portions are secured together and tightened about the supports by means of the bolt 26.

While I have described my invention in connection with the holding of order cards for electrical work, it is obvious that it can be employed for other purposes where it is desired to display a card in such a manner that it is protected but can be conveniently read.

Having thus described my invention in such full, clear, and exact terms that its construction and operation will be readily understood by others skilled in the art to which it pertains, what I claim as new and desire to secure by Letters Patent of the United States is:

1. A hold card holder having means for attachment to a support within convenient proximity to a switch or the like, said hold card holder having a back wall and a bottom wall and edge walls at both the lateral edges thereof, a transparent window functioning as a front wall, said window being spaced from said back wall and parallel thereto to provide a compartment for the temporary storage of orders, a closure for the top of said hold card holder, said closure having depending flanges on all sides thereof, and a hinge connection between said closure and said hold card holder, said hinge including a link and a pair of pivot pins projecting from the lateral edge walls of said closure and said hold card holder, said link being provided with a pair of slots for receiving said pins for slidable and pivotal movement of said closure relative to said hold card holder to opening and closing position.

2. A card holder having means for attachment to a support, said card holder comprising a first frame member with flanges projecting from the

5 opposite edges at both the front and rear, a second frame member with flanges projecting from opposite edges at the front thereof, and a rear wall member, said members being secured together with the front flanges of the two frame members in spaced relation and with the rear flanges of the first frame member secured to said rear wall, a transparent pane disposed between said spaced front flanges and functioning as a front wall, said window being spaced from said rear wall and parallel thereto to provide a compartment for the temporary storage of cards, and a removable closure for one end of said card holder secured thereto.

15 3. A card holder having means for attachment to a support, said card holder having a back wall and edge walls at three sides thereof, spaced flanges adjacent the front thereof, a transparent window functioning as a front wall, said window being supported between said flanges and being spaced from said back wall to provide a compartment for the temporary storage of cards, a closure for the open end of said card holder, said closure having depending flanges on all sides thereof, and a hinge connection between said closure and said card holder, said hinge including a link and a pair of pivot pins projecting from the lateral edge walls of said closure and said card holder, said link being provided with a pair of slots for receiving said pins for slidable and pivotal movement of said closure relative to said card holder to opening and closing position.

20 4. A card holder having means for attachment to a support, said card holder comprising a wall member and two flanged frame members secured together to provide a back wall, a bottom wall, edge walls at both the lateral edges thereof, and spaced flanges at the front thereof, a transparent window functioning as a front wall and disposed between said spaced flanges, said window and said spaced flanges being spaced from said back wall and parallel thereto to provide a compartment for the temporary storage of cards, a closure for the top of said card holder, said closure 25 having depending flanges on all sides thereof, and a hinge connection between said closure and said card holder, said hinge including a link and a pair of pivot pins projecting from the lateral edge walls of said closure and said card holder, said link being provided with a pair of slots for receiving said pins for slidable and pivotal movement of said closure relative to said card holder to opening and closing position.
